UNITED STATES PATENT OFFICE

ARTHUR J. BRANSTAD, OF EAU CLAIRE, WISCONSIN

DESIGN FOR A CASING FOR CIGARETTE VENDING MACHINE

Application filed April 25, 1931. Serial No. 39,622. Term of patent 14 years.

To all whom it may concern:

Be it known that I, ARTHUR J. BRANSTAD, a citizen of the United States, residing at Eau Claire, in the county of Eau Claire and State of Wisconsin, have invented a new, original, and ornamental Design for a Casing for Cigarette Vending Machine, of which the following is a specification, reference being had to the accompanying drawing, forming part thereof.

The figure is a perspective view of a casing for a cigarette vending machine showing my design.

I claim:

The ornamental design for a casing for cigarette vending machine, as shown.

Eau Claire, Wisconsin, April 20th, 1931.

ARTHUR J. BRANSTAD.
